US0D1103204S

(12) **United States Design Patent** (10) **Patent No.:** **US D1,103,204 S**
(45) **Date of Patent:** **** Nov. 25, 2025**

(54) **DISPLAY SCREEN OR PORTION THEREOF WITH GRAPHICAL USER INTERFACE**

(71) Applicant: **Aristocrat Technologies, Inc.**, Las Vegas, NV (US)

(72) Inventors: **Gary Penacho**, Henderson, NV (US); **Allon Engelman**, Las Vegas, NV (US); **Thomas Tuomey**, Las Vegas, NV (US); **Patrick Finch**, Las Vegas, NV (US)

(73) Assignee: **Aristocrat Technologies, Inc.**, Las Vegas, NV (US)

(**) Term: **15 Years**

(21) Appl. No.: **29/933,329**

(22) Filed: **Mar. 19, 2024**

Related U.S. Application Data

(63) Continuation of application No. 29/838,463, filed on May 12, 2022, now Pat. No. Des. 1,025,128.

(57) **CLAIM**

The ornamental design for a display screen or portion thereof with graphical user interface, as shown and described.

DESCRIPTION

FIG. 1 is a front view of a display screen or portion thereof with graphical user interface showing our new design according to a first embodiment;

FIG. 2 is a front view of a display screen or portion thereof with graphical user interface showing our new design according to a second embodiment; and,

FIG. 3 is a front view of a display screen or portion thereof with graphical user interface showing our new design according to a third embodiment.

The dashed broken line perimeter in the figures illustrates a display screen or portion thereof and forms no part of the claimed design. The remaining dashed broken lines in the figures illustrate portions of the graphical user interface that form no part of the claimed design.

1 Claim, 3 Drawing Sheets
